(57) **CLAIM**

The ornamental design for poke-through for air conditioner line set, as shown and described.

DESCRIPTION

FIG. 1 is a perspective view of the poke-through for air conditioner line set of the present invention showing my new design;

FIG. 2 is a top plan view of FIG. 1, the bottom plan view being a mirror image thereof;

FIG. 3 is a front elevation view of FIG. 1, the rear elevation view being a mirror image thereof;

FIG. 4 is a left side elevation view of FIG. 1, the right side being a mirror image thereof;

FIG. 5 is a perspective view of an alternative embodiment of the poke-through for an air conditioner line set;

FIG. 6 is a top plan view of FIG. 5, the bottom plan view being a mirror image thereof;

FIG. 7 is a front elevation view of FIG. 5, the rear elevation view being a mirror image thereof; and,

FIG. 8 is a left side elevation view of FIG. 5, the right side being a mirror image thereof.
